(57) **CLAIM**

The ornamental design for a storage rack for bakeware, as shown and described in the preceding Figures.

DESCRIPTION

FIG. 1 is a top perspective view of a storage rack for bakeware;

FIG. 2 is a top plan view thereof;

FIG. 3 is a front view thereof, the rear view being identical thereto;

FIG. 4 is a side view thereof; and,

FIG. 5 is a bottom plan view thereof.

The broken lines are included for the purpose of illustrating environmental features and form no part of the claimed design.
